KEYBOARD PERFORATOR TRANSMITTER

Ross A. Lake, Oak Park, Ill., assignor to Teletype Corporation, Chicago, Ill., a corporation of Delaware

Application October 4, 1937, Serial No. 167,139

6 Claims. (Cl. 178—25)

This invention pertains to printing telegraph apparatus and particularly to a keyboard actuated mechanism for the preparation of a signal control strip.

5 The primary object of the invention is to provide an efficient and easily operable keyboard apparatus for the production of signal control strips.

Another object is to render the key action of 10 such keyboard apparatus smoother and lighter to the touch.

A further object is to provide a means effective under certain conditions for removing from the key lever action the pressure imparted by 15 certain of its functional elements.

The present invention contemplates for the attainment of the above and other objects of the invention, a keyboard mechanism arranged with a plurality of keys operatively associated with 20 pairs of vertically movable permutation bars through which interponent bars of a perforating mechanism are moved selectively to control the operation of punch pins allotted thereto and to perforate a tape correspondingly.

25 According to the preferred embodiment of the present invention, the contacts for controlling the character counter have been more effectively located from the standpoint of enhancing the key action. Since the function of the counter 30 control contacts is to route an electrical circuit through either a registering magnet or a release magnet in the counter of the type; for example, in accordance with U. S. Patent No. 2,018,368, it is necessary to condition the counter control contact springs before the punch operating contact 35 is closed. Due to the inherent structure of prior designs of such apparatus, it was necessary to close the punch operating contact near the extreme end of the key stroke, making the "touch," 40 or key movement, undesirably deep. In the specific embodiment shown, both the depth of the stroke and the key pressure required to operate the perforator-transmitter have been reduced. The counter control contact assembly has been 45 placed on top of the keyboard casting in closer proximity to the selector mechanism.

A counter contact operating assembly is mounted within the keyboard casting and is provided with a plurality of small camming levers, which 50 engage the function key levers, and two vertical contact-operating arms, through the instrumentality of which the operation of the counter control contacts is accomplished early in the stroke of the keys. The small camming levers are so arranged that they will be pushed completely

to one side by the key lever during the first half of the key stroke. During the last half of the key stroke, there is no further displacement of the camming levers. The camming levers are articulated to horizontal bars so that the vertical motion of the key lever is transferred to a horizontal motion by means of which the counter control contact levers are enabled to actuate the counter control contacts. This construction precludes any unnecessary movement of the counter 10 control contact springs when the key is depressed to its maximum displacement. The counter control contacts are also completely operative before the code selection is set up so that there is ample margin between the routing operation of the 15 counter control contacts and the operation of the punch magnet contact.

Another feature of the invention resides in the provision of means for holding the universal bail depressed or out of engagement with the key 20 levers while the keyboard device is being operated to perforate a tape only. The specific form according to the present invention involves a flat spring used to disengage the trip pawl. The spring possesses the advantage of permitting the 25 trip pawl to be freed from the intermediate bell crank lever, which it normally engages, before the universal bail draws the trip pawl forward. The spring, therefore, performs the desired disengagement of the trip pawl from said bell crank 30 lever relatively early and provides a yield during the latter part of the travel of the tape-keyboard switch lever. By means of this feature, the load or effort of operating the universal bail has been removed from the key levers when the perforator- 35 transmitter is being used as a perforator only.

A better understanding of the invention may be had from the following description, taken in conjunction with the accompanying drawing, 40 wherein:

Fig. 1 is a longitudinal sectional view of the keyboard mechanism according to the present invention;

Fig. 2 is a plan view of the counter control contact assembly;

Fig. 3 is a simplified wiring diagram of an electrical control circuit that may be employed in connection with the present invention; and

Fig. 4 is a fragmentary perspective view to illustrate the control of the clutch mechanism 50 by the tape-keyboard switch lever.

Referring now to the drawing in which like reference characters are used to designate similar parts throughout the several figures, there is shown in Fig. 1 a keyboard 11 supported by a 55

base casting 12. Positioned to the rear of the base casting 12 and suitably journaled thereto is a pivot rod 13. To the pivot rod 13 a plurality of key levers 14 are rotatably mounted which are normally biased to horizontal position by individual springs (not shown), and which are provided, as is the usual practice, at their forward ends with keytops 15 arranged in banks.

Beneath the key levers 14, and extending transversely thereof, are a plurality of pairs of code bars 16. Each pair of code bars 16 comprises a bar 17 and a bar 18, and these bars are all provided at each end with vertical slots or notches 19 and 21 respectively, which fit over guide combs 22 and 23. The bars 17 and 18 are thus held against longitudinal movement, but are free to be shifted vertically in response to the operation of key levers 14.

Pivotedly mounted on rods 24 and 25 are pairs of rocker arms 26 and 27 interposed between code bars 17 and 18. The rocker arms 26 and 27 are substantially T-shaped, with their free ends formed with oppositely off-set lugs. Said lugs are disposed on opposite sides of the pivot rods 24 and 25 and are spaced some distance therefrom. One of the lugs of each rocker arm projects forwardly into a notch on the lower edge of the corresponding code bar 17, and its companion lug projects rearwardly beneath the companion code bar 18. With this arrangement, the depression of either code bar of the pair of bars 16 rocks the arms 26 and 27 and lifts the companion code bar. To the depending portion of the T-shaped rocker arms 26 and 27 is articulated a longitudinally movable permutation bar 28. Thus, when the code bars 17 and 18 are moved vertically in accordance with the depression of a key lever 14, the permutation bar 28 individual to a pair of bars 17 and 18 is moved longitudinally.

The key lever and permutation bar construction and arrangement are the same as disclosed in Patent No. 1,884,753 of October 25, 1932 issued to H. L. Krum, and for further details thereof reference should be made to the cited patent.

Each of the key levers 14 is arranged, when operated, to engage and depress one of the permutation bars of each pair of code bars 16 and to set these code bars in accordance with a character code combination. To achieve this object, the upper edges of the code bars 17 and 18 are notched to provide high and low portions in accordance with the respective codes. Also, the bars of each pair of code bars are complementary; that is, the notches of one bar are opposite the projections of its companion bar. The interconnection between the bars of each pair of bars 16 by means of the rocker arms 26 and 27 prevents the simultaneous depression of two key levers. If an attempt is made to operate more than one key lever at a time, the key levers can only be depressed for a short distance, when they will be blocked by the high portions of the code bars. By such construction, the simultaneous depression of two key levers and the transmission of an incorrect signal is prevented.

The perforator comprises a set of code punches 29 movable through an opening in upper and lower guide plates 31 and 32 and cooperative with a die plate 33 to perforate a tape 34. The plates 31 and 33 are spaced apart to form a tape guide. Intermediate the guide plates 31 and 32 is a stripper plate 35 which cooperates with shoulders on the punches, and due to the action of springs 36 operates to remove the punches clear

of the tape following the operation of a punch hammer 37. The code punches 29 are selectively operated by the actuation of the punch hammer 37 on a set of punch interponent bars 38 corresponding in number to the punches 29. Operatively associated with each of the bars 38 is a pivoted arm 39 which is connected to the permutation bar 28 by means of a link 41. The interponent bar 48 for the feed-hole punch pin is immovable and is fixed at its right-hand end (Fig. 1) to an arm 40 secured to the perforator frame 50.

The hammer 37 rocks about its pivot 42 and forms the armature of an electromagnet 43. The hammer 37 comprises a comb portion 44 or guiding the interponent members 38 and 48. In accordance with the disclosure in copending application Serial No. 151,364, filed July 1, 1937 by C. W. Burcky, the hammer surface of portion 44 comprises two intersecting planes 45 and 46 and a raised rib 47 on one of said planes. The code punch interponent bars 38 are adapted to slide on the plane surfaces 45 and 46, while the feed-hole punch interponent bar 48 cooperates with the raised rib 47. Thus at all times the upper surface of the feed punch interponent bar 48 is higher than the corresponding upper surfaces of interponent bars 38. The function of the two intersecting planes and the raised rib is to compensate for the rocking motion of the punch hammer 37 to maintain substantially the same relation between interponents 38 and 48 in both the clockwise and counterclockwise positions of the hammer 37. When a punch hammer such as hammer 37, having two planes and a raised rib 47 for the feed hole punch interponent bar 48 is used, it is desirable to adjust the lateral position of the interference bar 48 (rightward or leftward position, as viewed in Fig. 1) under the feed hole punch. Accordingly, the arm 40 on which bar 48 is mounted is made adjustable by providing for the insertion of shims 49.

Pivotedly carried at one end of punch hammer 37 is a pawl member 55 which cooperates with ratchet teeth 56 of a spacing roller 57 which is provided with feed pins 58 adapted to mesh with the feed holes which are invariably perforated in the tape 34. Thus, when the magnet 43 is energized and the hammer 37 is rocked to its clockwise position, pawl 55 is raised to engage a tooth 56 on the spacing roller 57. Then, upon deenergization of magnet 43, spring 53 actuates the hammer 37 to its counterclockwise position and draws pawl 55 downwardly, which movement causes the spacing roller 57 to be rotated counterclockwise one angular step to effect the spacing of the tape 34 one unit distance.

In addition to the five pairs of code bars 16 there is provided, as disclosed in Patent No. 1,965,602, a universal bar (not shown), associated with a rocker assembly the bar 28 of which is connected by a link 41 to a contact operating lever (not shown) associated with a pair of contacts 52 (Figs. 1 and 3) for controlling the operation of the punch magnet 43. Upon operation of any key lever 14, contacts 52 are closed and an energizing circuit for perforating magnet 43 is completed, causing magnet 43 to operate, whereupon hammer 37 will be rocked to its clockwise position, thereby effecting the perforation of the tape 34 in accordance with code combinations. Upon the deenergization of magnet 43 the punches 29 are withdrawn and the tape 34 is advanced one step under the influence of spring 53.

To indicate to the operator the number of code

signals perforated in the tape so that he may be apprised when a predetermined number of character code combinations have been perforated in the tape, or a number sufficient to fill a line of printing, a counter, the electrical control elements of which are indicated in Fig. 3 by reference numeral 10, is positioned to the right of the main machine, and may be of the construction shown in U. S. Patent No. 2,018,368. Consequently, by observing the position of a pointer with respect to the scale of the counter 10, as fully disclosed in said patent, the operator can constantly note the number of character code combinations perforated in the tape from the beginning to the end of the line, and can determine the position at which the carriage and/or counter return key should be depressed for correspondingly perforating the tape to control a receiving printer. In order to operate the counter 10 to indicate the condition referred to, an electromagnet 51 is provided (Fig. 3), which functions for each key operation (unless its circuit is opened as noted hereinafter) to cause the advancement of an indicating pointer (not shown) a predetermined amount. The circuit for electromagnet 51, as indicated in Fig. 3, extends through the contact springs 61 and 62 of contact bank 60, and the contact springs 52. In other words, the contact springs 61 and 62 are normally closed and are so related to the contacts 52 that when the latter contacts are closed for causing energization of the punch electromagnet 43, a circuit is likewise completed through the electromagnet 51. Upon the completion of the circuit for the electromagnet 51, it is actuated and causes the associated pointer to move over the scale for indicating the number of character code combinations perforated in the tape as disclosed in Patent No. 2,018,368. When a predetermined number of character code combinations have been perforated in the tape, or a number sufficient to fill a line of printing, a mechanism on the counter 10 is operated to cause the closure of contact 54. The closure of this contact completes the circuit for a lamp 59, which signals the operator of the approach of the end of the line. The operator in noting this signal operates the carriage return key and in so doing, an energizing circuit is completed for an electromagnet 78, in a manner which will presently appear, to control the restoration of the pointer of the counter 10 to its normal or zero position.

It is desired in connection with certain of the function key levers, such for example as shift and unshift, line feed and carriage return, to prevent the operation of the counting mechanism or counter 10. Upon the depression of these particular key levers, actuation of counter 10 is prevented by a camming lever arrangement which comprises an important feature of the present invention. Having reference to Fig. 1, the camming levers 65, 66, 67, and 68 are pivotally mounted upon a bracket 69 which is secured to the base 12 through a pair of lugs 70 (only one of which is indicated in Fig. 1). The camming levers 65, 66, 67, 68 are provided at their upper ends with cam portions which cooperate with the function key levers of the series of key levers 14. Each of the camming levers is provided with a vertical projection 71 to prevent the accidental disengagement of said levers from cooperative relation with their associated key levers 14. Camming levers 65, 66, and 67 are, in the present embodiment, disposed to the rear of bracket 69 and their lower ends are pivotally articulated to a horizontal bar

72. At the left-hand end of bar 72 is fixed a vertically directed contact operating member 73.

Camming lever 68 is mounted on the forward face of bracket 69 and is pivotally articulated to a horizontal bar 74. Bar 74 is also pivotally connected by means of a link 75 to bracket 69 so that bar 74 is movable with respect to bracket 69 in a parallel motion manner. There is also fixed to the left-hand end of bar 74 a contact operating member 76, corresponding to member 10 73.

Contact operating members 73 and 76 cooperate with contact springs 61, 62, and 63 of contact bank 60 (Figs. 1 and 2) which is carried on a bracket 77 mounted on base casting 12. When 15 those key levers 14 allotted to the shift, unshift, and line feed functions are operated, they are caused, through the cam portions of their associated camming levers 65, 66, or 67, to actuate said camming levers clockwise (as viewed in 20 Fig. 1) to move bar 72 leftwardly to actuate contact operating member 73 correspondingly, which movement causes contact spring 62 to be separated from contact spring 61, thus breaking the circuit to the counter operating magnet 51. It 25 is understood that the punch operating contacts 52 are invariably operated upon the depression of a key lever 14 through the instrumentality of a universal bar previously alluded to, but the circuit for the punch operating magnets is independent of the circuit for the counter or stepping magnet 51, said circuits being in parallel.

The depression of the carriage return key lever will actuate camming lever 68, through the cam portion thereon, in a counterclockwise direction, 35 which movement imparts rightward motion to bar 74 to actuate contact operating member 76 in a corresponding direction. This movement of member 76 causes the disengagement of springs 62 and 61 and the engagement of contact springs 61 and 63 to complete an energizing circuit for an electromagnet 78 in the counter 10 which controls the restoration of the pointer of the counter 10 to its normal or zero position in the manner disclosed in Patent No. 2,018,368. The 40 energizing circuits for the electromagnets 51 and 78 may be traced over the conductors clearly disclosed in Fig. 3. It will be noted that the camming levers are so arranged that they will be pushed completely to one side by their associated key levers during the first half of the stroke of said key levers. During the last half of the key stroke, there is no further displacement of the camming levers.

When the perforator mechanism, according to 55 the present invention, is employed in combination with a keyboard transmitter, the permutation bars 28 are each provided with a forked member 81 (Fig. 1). Articulated to member 81 is a depending arm of a locking latch 82 pivoted 60 on a common shaft 83. In this manner, locking latches 82 are articulated to the permutation bars 28 and are adapted to be rocked about pivot shaft 83 to either of two positions. Associated with latches 82 is a corresponding series of contact 65 levers 84 for making and breaking individual contacts 85. Contact levers 84 cooperate with individual contact cams on cam drum 86 mounted on the transmitting shaft 87 provided with a clutch mechanism 88 (Fig. 4) controlled by a 70 trip member 89, as set forth in U. S. Patent No. 1,965,602. U. S. Patent No. 1,585,472 of August 10, 1926 discloses the cam drum assembly 86 and reference may be had to such patent for further details thereon. Trip member 89 cooperates with

a T-lever 91 pivoted to bracket 82. The depending arm of T-lever 91 is pointed as at 93 and is in the path of a shoulder 94 formed in a slidable member 95. The member 95 is secured to a universal ball 96 which is rotatably mounted on studs 97 (Fig. 1), and which is rotated upon the depression of any of the keys of the keyboard. The universal ball 96 and the member 95 are normally urged upwardly and rightwardly, respectively, by a spring 98. When the universal ball 96 is depressed, the member 95 will be moved to the left against the action of spring 98 and the shoulder 94 will engage the pointed end 93 of the T-shaped lever 91 and cause said lever 91 to be rotated clockwise (as viewed in Fig. 4), which action will cause trip member 89 to be rotated out of engagement with portion 90 of clutch 88 thus permitting the clutch 88 to operate through one complete cycle in well-known manner. The universal ball 96 is returned to its normal position by spring 98 so that the member 95 will likewise be urged to its normal position.

In the operation of the transmitting unit, the depression of a key lever 14 moves the bars 17 and 18 permutably in accordance with a predetermined code combination, the setting of which, through permutation bars 28, determines the positions of the locking latches 82. The rotation of cam drum 86 is initiated substantially simultaneously with the setting of the locking latches 82, through the instrumentality of trip member 89 which releases the clutch 88 for rotation as previously described, and the locking loop 99, controlled by a cam 101 carried on a cam assembly freely mounted on shaft 87, is permitted to rotate in a counterclockwise direction (Fig. 1) to lock the latches 82 in their selected positions. The setting of latches 82 determines whether the contact levers 84 shall or shall not be affected by their associated cams on cam drum 86 to transmit, through contacts 85, over a signal line to the receiving station, a predetermined code combination of signaling impulse. The respective notches in the cams on cam drum 86 are arranged in a helical progression so that upon the rotation of the cam assembly, the contacts 85 controlled by levers 84 will be operated successively. The apparatus herein disclosed is operated in accordance with an equal length letter code, in which each code combination is a permutation of marking and spacing conditions, and is preceded by a start impulse and followed by a stop impulse according to the familiar start-stop system.

With the apparatus according to the present invention, it is desired, in some instances, to transmit directly to a line circuit, code combinations of impulses representative of the character keys operated, while in other instances it may be more practical first to perforate a tape in accordance with the key operated, and then to transmit subsequently the signal corresponding thereto by means of a tape transmitter. To provide for the several possible conditions of operation, a switch is arranged in the keyboard apparatus to control the transmission of impulses directly to the line circuit, the perforation of a tape only, or the operation of the transmitting distributor and the perforator simultaneously. The control of these various conditions of operation is fully disclosed in U. S. Patent No. 1,965,602. However, according to the present invention, the aforementioned switch has been modified to improve the operation of the apparatus in effecting a transition from transmitting

only, or transmitting and perforating, to perforating only.

As set forth in said patent, to control these various operations, a switch lever or member 102 is provided which is pivoted at 103, and which assumes three positions; namely, an upper position 104 (Figs. 1 and 4), a middle position 105, and a lower position 106, and is held in these representative positions through the cooperation of a bracket 107. As shown in Fig. 4, switch member 102 is provided with a bifurcated end which cooperates with a group of contacts, not here shown, but which is fully described in Patent No. 1,965,602. That position of the switch member 102 indicated 104 is referred to as the "keyboard" position and is a position wherein direct keyboard transmission of signals to the line is effected; that is, each time a key lever is operated, the transmitting cam drum 86 is rotated a single cycle to transmit a code combination of signals through contacts 85 to the line. The position of switch member 102 indicated as 105 is known as the "tape and keyboard" position, and is that position wherein the perforator and transmitting mechanisms are conditioned to operate simultaneously.

The position of the switch member 102 indicated as 106 is known as the "tape" position, and in this position the transmitting cam drum is not initiated into rotation; that is, the perforator may be operated without operating the keyboard transmitter. In moving the switch member 102 to this particular position, the member 95 is moved through the instrumentality of a flat spring member 108, which is secured to switch member 102, to a position where its shoulder 94 is out of alignment with the pointed end 93 of the T-shaped lever 91. Consequently, when the universal ball 96 is operated, the member 95 will not operate the clutch release lever 91, and hence the clutch 88 will not be released for rotation. Under these conditions, impulses will not be transmitted to the line circuit, as previously described, upon the depression of the character keys. The spring 108 possesses the advantage of permitting the member 95 to be freed from point 93 of the T-shaped lever 91, which it normally engages, before the universal ball 96 draws member 95 forwardly. The spring 108, therefore, performs the desired disengagement of the member 95 from the lever 91 relatively early and yields during the latter part of the travel of the switch member 102.

Carried also on pivot 103 and adjacent to switch member 102 is a lever arm 109. Mounted on lever 109 at 111 is an eccentric stud 112. The depending arm 113 is integral to lever 109. The function of stud 112 is to control for adjustment purposes the angular relationship between levers 102 and 109. Stud 112 cooperates with shift member 102, and lever 109 cooperates through arm 113 with universal ball 96 in such manner that upon the depression of the switch member 102 to its lowest position, indicated 106 in Fig. 1, switch member 102 engages stud 112, and through arm 113 causes the depression of universal ball 96 in which depressed position the universal ball 96 is retained so long as switch member 102 remains in said lowermost position. Thus, upon the depression of switch member 102 to its lowermost position, two operations occur simultaneously; that is, the freeing of shoulder 94 from point 93 by means of spring 108, and the depression and retention of universal ball 96. By means of this feature, the load or effort of operating the universal ball 96 has been removed

from key levers 14 when the apparatus according to the present invention is being used as a perforator only. However, each time a key lever 14 is operated, the universal bar previously alluded to for operating the punch magnet control contacts 52 will be actuated, closing contacts 52 to complete a circuit to effect the operation of the perforator magnet 43.

While the present invention has been illustrated and described with reference to a particular structure, it will be understood that various modifications may be made without departing from the spirit of the present invention. Hence, all forms coming within the scope of equivalency of the appended claims are intended to be covered by the invention.

What is claimed is:

1. In a telegraph unit, a selector mechanism, operating elements therefor, a counter for recording the number of operations of said selector mechanism including a stepping magnet responsive to the operation of the selector mechanism and a release magnet operative to restore said counter, and cam means controlled by said elements for controlling said magnets.
2. In a telegraph mechanism, a selector unit, operating elements therefor, a counter for recording the number of operations of said selector mechanism including a stepping magnet responsive to the operation of the selector mechanism and a release magnet operative to restore said counter, counter routing contacts, and camming levers operated directly by said elements for controlling said contacts to control said magnets.
3. In a telegraph keyboard unit, a selector mechanism, a series of key levers, a counter for recording the number of operations of said selector mechanism including a stepping magnet responsive to the operation of the selector mecha-

nism and a release magnet operative to restore said counter, counter operating contacts, and camming levers operated directly by said key levers for controlling said contacts to control said magnets.

4. In a telegraph keyboard unit, a selector mechanism, a series of key levers, a counter for recording the number of operations of said selector mechanism including a stepping magnet responsive to the operation of the selector mechanism and a release magnet operative to restore said counter, counter routing contacts, operating members for said contacts, and parallel motion mechanism carrying said operating members and actuated directly by said key levers to operate said contacts in routing manner to control said magnets selectively.

5. In a telegraph keyboard unit, a selector mechanism, a series of key levers, a counter for recording the number of operations of said selector mechanism including a stepping magnet responsive to each operation of the selector mechanism and a release magnet operative to restore said counter, counter control contacts, operating members for said contacts, and cam means operated directly by said key levers for controlling, through said members, said magnets selectively.

6. In a telegraph unit, a selector mechanism, operating elements therefor, a counter for counting the number of certain operations of said selector mechanism including a stepping means responsive to the operation of said selector mechanism whereby said counter is operated progressively step by step, and means controlled by certain of said elements for rendering said stepping means ineffective and thus preclude the operation of the counter.

ROSS A. LAKE.
